Term of patent 14 years

(Cl. D34—4)

FIG. 2

Figure 1 is a side elevational view of a puppet doll or similar article showing my new design (the side elevation being the same from either side).

Figure 2 is a front elevational view of the puppet doll or similar article shown in Figure 1. (However, the arms and hands are in slightly different position in this figure for greater clarity.)

We claim:

The ornamental design for a puppet doll or similar article, substantially as shown and described.
